TILTING DOOR

Edmond Wanner, Geneva, Switzerland

Application December 20, 1935, Serial No. 55,323
In Switzerland May 17, 1935

3 Claims. (Cl. 20—19)

The invention relates to a tilting door, intended more particularly for sheds, having side posts widely separated from each other.

The door according to the invention is characterized in that it is braced by means of an exterior girder, so disposed that in the open position, in which the door panel takes an approximately horizontal position under the spring-beam, the latter is situated in one of the two dihedrons formed by the panel with its girder.

The drawing shows two embodiments of the subject of the invention, given by way of example.

Figs. 1 and 2 each represents one of said embodiments, in cross section, the section being taken on a plane perpendicular to the plane of the opening closed by the door.

In Fig. 1 the upper part 1 shows part of the truss of the roof of the shed, the slope of which is so directed that the highest part of the roof 20 is above the spring-beam 2 while the gutter is on the right, in the position shown.

The tilting door consists of a panel 3 intended to obturate the free space between the ground, the side posts and the spring-beam of the shed. 25 The distance between the side posts is supposed to be relatively great, i. e. the shed is supposed to be very wide. This circumstance necessitates the provision of a door panel forming lengthwise a very rigid girder, as said panel is intended to come and lodge approximately horizontally under the spring-beam, in the position shown in dot and dash line at 3' when the door is opened. It is clear that the small binders 4 forming the panel drawn, of relatively small thickness, do not permit of obtaining the necessary rigidity.

Said rigidity could be increased by providing a thicker panel, but this would be to the detriment of the free height of the opening once the door opened, unless the spring-beam be disposed to a 40 certain extent higher thus increasing the total cubage of the construction.

In the example shown, the necessary rigidity of the panel is obtained without increasing the thickness of the latter, by applying to it an exterior box girder 5 integral with the panel, with which said girder forms two dihedral angles approximately supplementary.

As will be seen in the position in dot and dash line 3', 5' of the open door, it is then easy to bring the girder 5 outside the shed, before the spring-beam, so that the latter comes and lodges in one of the two dihedrons formed by the panel 3 with its girder 5.

Said disposition realizes several advantages. 55 In the first place, it realizes the advantage of

permitting of constructing doors the rigidity of which permits of suspending them above relatively long door openings, without the thickness of the door panels and consequently the height lost in the opening of the shed being in any way exaggerated. In the second place, the arrangement of a girder, such as the girder 5 has the effect of displacing the centre of gravity of the whole door outside the panel, for example to the point 6, and this arrangement permits of a suspension by the centre of gravity by means of cables 7 which are situated outside the shed and of raising the door vertically along the vertical guides 8 and of bringing without further agency the girder 5 to 5', before the spring-beam.

As regards the arrangement of the counterpoises, connecting bars and levers, guiding the door during its tilting, it is clear that any suitable arrangement may be used, as the invention is not concerned with this part of the problem.

While in the example of Fig. 1, the pulleys 9 of the cables supporting the door may be fixed to the shed itself, for example to the side posts of the latter, said possibility is no longer possible in the example according to Fig. 2, in which the slope of the roof 10 is contrary to that represented in the previous example, as at least a part of the water runs in the gutter 11 fixed along the spring-beam. In that case, it is necessary to dispose the pulleys 12 higher than the free part 20 of the roofing of the shed, that is to say at the end of the sliding guides 13 of the door, said guides having for this reason to form pillars, girders or similar bearers, placed before the side posts, integral with them or replacing them 25 wholly or partially.

The door is here formed by means of a panel 13, divided for example into frames, themselves filled with wood or metallic sheet iron while the girder 14 is a simple double T-iron. The suspension is also effected here at the centre of gravity 15. As regards the manner in which the door tilts, it may be effected in any manner whatever, its opening position being shown in dot and dash line at 13', 14'.

The girder ensuring the rigidity of the door panel, be it simple or box, may be executed latticed or plain, and it is not necessary that it should have the same width or thickness over its whole length, it being quite possible for it to have a variable section so as to offer at each of its points a resistance proportional to the moment of flexion to which it is subjected when the door is suspended in its open position.

What I claim is:—

1. A tilting door for a door opening with side posts spaced a distance apart and a door header, having a transverse reinforcing girder secured upon said door intermediate the top and bottom edges thereof, said door, when open, being raised in horizontal position beneath the door header so that said header is disposed within one of the two dihedrons formed by said door and said reinforcing girder and said top and bottom edges of the door are free.

2. A tilting door according to claim 1, wherein the door tilts upon a pivotal mounting having its axis spaced a distance from the door proper upon the same side of the latter with the girder and disposed at least in close proximity to said girder.

3. A tilting door according to claim 1, wherein the door tilts upon a pivotal mounting having its axis spaced a distance from the door proper upon the same side of the latter with the girder and disposed within the outline of said girder.

EDMOND WANNER.
